DRIVING CENTER

Edgar A. Terrell, Charlotte, N. C., assignor to
Terrell Machine Company, a corporation of
North Carolina

Application, February 19, 1941, Serial No. 379,596

13 Claims. (Cl. 142—53)

My invention relates to an improved driving center for use in a lathe or boring machine or the like. It is adapted for rotatively driving a work piece of wood, fiber, or other material which is soft enough to permit driving dogs having wedge shaped ends to enter into the material. My driving center may be used on work which has a prebored hole for centering or where a point center is to be used in solid wood.

The driving center of my invention comprises broadly a body portion, a sleeve supported thereby, driving members maintained in spaced relationship by the sleeve, and a work-engaging center disposed concentrically with the sleeve. In a typical embodiment, the body portion is a hollow cylinder having a tubular extension for mounting in the lathe, and the sleeve has radially arranged keyways for engaging and holding the spaced driving members. These driving members may advantageously have flat sides for positive engagement with the keyways and have wedge shaped outer ends that extend beyond the sleeve for effecting positive driving contact with the work piece. A pointed center pin may be slidably located or fixedly positioned within the sleeve, as desired, for contacting and centering the work to be machined.

In some cases it is desirable to provide additional contact with the work piece and for this purpose the work-engaging face of the above described sleeve may be machined to form a circular knife edge. This circular knife extends slightly beyond the wedge shaped ends of the driving members or dogs and accordingly enters the work piece just in advance of the driving dogs. It helps prevent slipping and splitting of the work piece and insures more perfect concentricity of the work piece with the work engaging parts of the driving center as explained in detail below.

Generally speaking the sleeve carrying the driving dogs may be of any desired maximum diameter or may be reduced to any required minimum diameter to permit maximum engagement of the work piece and at the same time provide clearance for the cutting tool to operate near the sleeve without touching it. Similar changes in size and arrangement of the center pin may be made to accommodate varying types of work pieces, in accordance with my invention.

One of the novel features of my lathe driving center is the use therein of individually adjustable and replaceable driving dogs having maximum driving power without tendency to slippage. These dogs may be made easily removable and replaceable, or adjustable in length for different

types of work by being tapped at one end into a separate base member. This member serves as a stop or base for the aforementioned sleeve.

The predominant length or shank of the driving dogs according to a preferred embodiment is nonrounded, i. e. flat-sided and advantageously rectangular in cross section so as to effect firm positive driving contact with the similarly shaped slots or keyways in the sleeve in which they are located. This arrangement prevents rotation of the driving dogs about their axes during operation of the driving center and provides adequate support of the driving dogs from the sleeve against lateral movement. The outer ends of the driving dogs, opposite the tapped ends, have tapered knife-like edges for penetrating and driving the work piece with minimum risk of splitting the work piece.

If desired, driving dogs of round cross section throughout their full length except for the knife-edged ends may be used. They may be prevented from rotating by locking screws threaded into the base member, as described below. Rounded slots in the sleeve supporting these round driving dogs will prevent twisting of the dogs about the center axis. The same thing would be true if the square type slot were retained so long as axial support was provided by the sidewalls of the slot at the point of tangency on both sides of the rounded driving dog.

The center pin, which is usually positioned inside of the sleeve, has a pointed outer end that extends beyond the sleeve for engaging and centering the work piece. Where the latter is solid a nonslidable point type center pin may be used. Where the work has a prebored hole for centering I have found it advantageous to use a slideable conical shaped center pin, which is adapted to compensate for slight variations in the diameter of the bore before permitting the work piece to move endwise into final driving position. This slideable center pin may have a double cone form which shortens the length by making the smaller diameter tip portion with a greater included angle and the larger diameter work engaging portion with a lesser included angle; thus providing a greater wedging action under the same applied end pressure on the work. The main purpose of this is to insure better seating of the work on the center and less tendency to slip out of axial alignment than is the case with conventional drivers.

My driving center provides simple and positive means for endwise positioning of the work piece as hereinafter described and also means for re-

ducing greatly any tendency of the work to slip sidewise or at right angles to its axis as the driving dogs are forced into the driven end. This latter result is obtained, as above suggested, by setting the circular knife edge slightly in advance of the driving dog knife edges so that the work is supported against motion away from the true axis of the machine by both the conical point center and by the knife ring which also engages it prior to engagement with the driving knife edges. 10

In the operation of my driving center on pre-bored work even where the prebored hole assumes an elliptical shape, concentricity of the turned surface with the center hole is obtained. This is accomplished by providing sufficient pressure of the conical center pin engaging the hole to expand the flat sides of the hole enough to permit its entire circumference to be engaged by the cone, before the knife edge of the sleeve engages the work to give further support against sidewise motion. Then both the conical center and the circular knife will give combined support to prevent the final force applied to push in the driving dogs from causing displacement from the axis. The circular knife assists further in resisting side stress imposed by the cutting tools and in addition prevents the ring of material engaged by the driving dogs from spreading. The material is therefore made stronger and denser in that area which is engaged by the driving dogs. 20

This is made possible by the knife edge of the sleeve being beveled inwardly so that it compresses the material which is brought into contact with the face of the sleeve. The knife ring effectively prevents spreading of the end fibers lying between it and the conical center or center point. Since the material engaged by the driving dogs is thus strengthened it follows that greater driving force can be secured from driving dogs of a given size than would be the case if the end fibers were not supported and compressed by the outer knife ring. 30

It will also be understood that my positively engaged driving dogs, and circular knife when used, provide substantially greater driving force than can be obtained from a screw type center where the driving power is transmitted solely by engagement of the screw with the material. This is true regardless of whether the screw is adjustable or mounted in fixed position. Moreover, any tendency of the work to split radially when the driving dogs are driven into it is prevented from extending beyond the circular knife edge and thus much work is saved which would otherwise be damaged beyond repair. 40

As an alternative in my invention when exceedingly thin walled work is being turned, the circular knife portion of the sleeve may be omitted. In such case the diameter of the sleeve may be reduced enough to expose the open slots formed by the sides of the keyways which contain the driving dogs.

The above described double cone construction of the center pin is desirable although not essential to the operation of my device and is used primarily to gain the aforementioned advantages and to save material through shortening the total length of the cone. 50

As heretofore mentioned, my center may be used on work which has a prebored hole on which the work is to be centered or on solid work into which a center pin must be forced. The centering of prebored work is best accomplished

by using a spring pressed conical center point slidably mounted to permit slight endwise movement to compensate for slight variations in hole diameter, while the centering of solid work may require a center point fixedly held against axial movement. My driving center provides for both uses as will be understood from the description to follow. 5

It will be understood that endwise motion between the work piece and the driving center assembly is relative. Accordingly under some circumstances the driving center assembly may be moved endwise into complete engagement with a stationary work piece while under other circumstances the work piece may be moved endwise into engagement with a non-moving driving center assembly. A third condition would arise if it were desirable to move both the driving center and the work piece toward each other. 15

Certain of the novel features of this invention are set forth with particularity in the appended claims; organization of parts and method of operation of the invention will be more fully understood from the following detailed description taken in conjunction with the accompanying drawings which illustrate specific but nonlimiting embodiments and in which:

Fig. 1 is a longitudinal sectional view of my driving center; and a fragment of a prebored work piece; 30

Fig. 2 is an end view of the driving center shown in Fig. 1;

Fig. 3 is an elevational view of the driving dogs and supporting member therefor;

Fig. 4 is an end view of the assembly shown in Fig. 3;

Fig. 5 is a detail of one of the driving dogs;

Figs. 5A and 5B are sectional views along the lines A—A and B—B respectively of the driving dog shown in Fig. 5; and Figs. 5C and 5D are end views of this driving dog;

Fig. 6 is an elevational view of the sleeve with keyways;

Fig. 15 is an end view of the driving center shown in Fig. 14;

Fig. 16 is an elevational view of a modification of the driving dogs shown in Fig. 3, and

Fig. 17 is an end view of the assembly shown in Fig. 16.

70 Referring now to the several figures in the drawings, wherein like reference characters identify similar parts, the driving center assembly as illustrated in Figs. 1 and 2 comprises a cup-shaped body portion 10 having a tubular shank 75 11 which is adapted for attachment to the spin-

die in a lathe or other suitable driving means. Resting on the bottom of the cup 10 is a disk-shaped base member 12 of suitable diameter to fit saugly within the inner circumference of the cup and having sufficient thickness for mounting of the driving dogs 13.

The disk 12 has tapped holes 14 spaced around the face of the disk equidistant from the center, for receiving the threaded ends 15 of the driving dogs 13. This threaded connection prevents relative endwise motion between the disk and the driving dogs during operation, although effective lengthening or shortening of the dogs can be obtained when desired by rotary motion of the dogs; that is, advancing or retarding the threaded ends into or out of the tapped holes of the disk.

The sleeve 16, the general features of which are referred to hereinabove, is located inside the cup 10 and in relatively close contact therewith. It rests on the disk or base member 12 and is held in fixed position by a set screw 17 that prevents both axial and rotary motion of the sleeve. The sleeve 16 serves several purposes of which the following are principal examples:

The inner end of the sleeve resting on the disk 12 prevents the latter from moving endwise away from the bottom of the cup.

The sleeve is slotted axially along the inner surface to form keyways for receiving and holding the driving dogs 13. The keyways and dogs are flat sided or of such cross-section that the dogs cannot rotate when located in the keyways. Thus when the sleeve is assembled with cup 10, disk 12, driving dogs 13 and set screw 17, the assembly is locked together as a unit.

The side walls 18 of the slots or keyways support the driving dogs 13 against torsion imparted by the work piece and prevents the dogs from bending around the center.

The outer end of the sleeve, in this embodiment, is machined down to form a circular knife edge 19 which enters the work piece and helps to support it against axial displacement from cutting stresses, as described generally above.

The end face 20 of the sleeve lying inside of the circular knife edge has a flat surface that serves, during operation, as a stop against which the work piece is forced and thereby serves to position the work piece endwise.

Inside of the sleeve 16 is slidably positioned a conical center pin 21. This pin is limited in endwise motion by a screw 22 which is threaded into the sidewall of the sleeve 16 and which has a point 23 projecting into a longitudinal slot 24 cut in the side of the cylindrical body of the center pin 21. This screw permits the conical center to slide longitudinally along the length of the slot but no further.

At the inner end of the center pin 21 there is a spring adjusting screw 25 which is tapped into the body of the center pin and held in position by lock nut 26. The unthreaded end of this screw has a spring engaging portion 27 that engages a compression spring 28. This spring works in a hole in shank 11 of cup 10 and rests against a shoulder 29. This compression spring forces the conical center pin 21 outward until the inner end of slot 24 rests against screw point 23 and prevents further motion.

The spring 28 constitutes resilient means for resisting the inward travel of the conical center pin 21 and the screw 25 serves as means for adjusting the resistance to meet the requirements of any particular work piece on which the cen-

ter is being used. Thus, less endwise pressure of the cone may be provided for thin walled work which is easy to split and greater pressure for harder or thicker walled work where the danger of splitting is less.

The outer end of the center pin 21 is tapered in a double cone form, comprising an outermost portion 30 of relatively large included angle and an adjacent secondary work-engaging portion 31 of lesser included angle. The outermost cone section 30 serves to shorten the overall length of the biconical member and at the same time permits work having a prebored hole to be picked up and guided onto the work engaging cone surface 31.

The purpose of the lesser included angle of the work-engaging surface of the cone section 31 is to provide greater pressure against the inner surface of the work piece; to cause the cone to enter the prebored hole more easily and by virtue of greater wedging action to exert greater pressure against the inner edges of the work piece. Thus, it insures more perfect centering if the hole is not perfectly round or if there should be splinters or burrs left within the edge of the hole from previous operations. Also, if the hole is slightly elliptical the wedging action of the cone will force the flat sides of the ellipse apart and will cause the sides lying on the long axis to engage the cone rather than be thrust to one side which is often the case when a cone of greater included angle is used.

When the pressure of the work piece against the cone has become sufficient to overcome the resistance of spring 28 the center pin 21 slides inwardly. This permits the work piece to engage successively circular knife edge 19 of sleeve 16 and then wedge-shaped ends 32 of driving dogs 13. Finally, the end of the work piece such as shown at 33 in Fig. 1 comes in contact with the squared end face 20 of the sleeve 16. The circular knife edge 19 is tapered inwardly as shown at 34 to compress the material of the work piece as it is forced into position and thus provide a ring of denser material, between the circular knife and the conical center pin, to be engaged by the driving dogs 13. This arrangement makes it possible to transmit more power without tearing the material.

Referring now more specifically to the driving dogs, I have shown in Figs. 3, 4 and 5 an advantageous form. In the embodiment illustrated the shank or main body portion 35 of the driving dog 13 is square in cross-section as shown in Fig. 5B. In operation this square portion engages the flat side walls 18 that define the keyways in the sleeve 16. The threaded end 15 is rounded as indicated in Figs. 5A and 5C. The work engaging end is wedge-shaped forming a knife-like edge 32 as shown in Figs. 3 and 5D. As illustrated in Figs. 3 and 4, the five driving dogs are radially arranged about the center axis of the disk 12. They are spaced equal distances apart and from the center of the disk although this is not essential.

By virtue of the tapped connection between the disk 12 and the threaded portion 15 each of the driving dogs is individually adjustable and replaceable. Sufficient length is provided to permit regrinding of the knife edge 32 if the latter becomes worn, dull or is broken off. In such case the repaired member is threaded less distance into the disk 12 so as to make it the same effective length as the other driving dogs. Also, the outward extension of knife edged portions 32

beyond face 20 of sleeve 16 may be adjusted to the exact needs of the work being done. Thus, adjustments of one or more of the driving dogs in either direction may be obtained by turning the driver in the desired direction, and by virtue of this adjustability of the driving dogs their effective life is materially increased.

As illustrated in Figs. 6 and 7, the sleeve 16 is cylindrical in shape and has the keyways, for the driving dogs, extending the full length of the sleeve. The keyways or slots 18 are open on the side adjacent the center pin. They are radially arranged and are equidistant.

To disassemble my driving center, for adjustment of the driving dogs or for other reasons, it is only necessary to back off the set screw 17, slide the sleeve 16 out of the cup 10, and then withdraw the disk 12 with attached driving dogs, from the sleeve. Once the disk is removed the driving dogs may be adjusted or removed easily by rotative movement as described above.

It will be appreciated from the foregoing that a series of different diameter sleeves can be made to fit within the cup 10 and having external extended diameters, such as shown at 36 in Fig. 1, of different dimensions to fit various sizes of work pieces and internal diameters of varying sizes to receive conical center points having body portions of varying diameters. In such cases the tapped holes in disk 12 may be spaced as required to provide proper alignment of the driving dogs 13 with slots in the sleeves. Likewise, it will become apparent that for each inner sleeve diameter there may be a series of conical center points, each having the same body diameter to fit the sleeve, but having work engaging cone surfaces in a series of diameters capable of fitting a wide range of hole sizes. Illustrative examples of these variations and alternatives are given in Figs. 8-13, a more detailed description of which now follows.

In the driving center shown in Figs. 8 and 9 the cup 10, sleeve 16, and main body portion 21 of the center pin have been maintained substantially the same in size and shape as the corresponding parts shown in the preceding figures. This is also true of the sleeve extension shown at 36. The change, however, comes in the biconical sections 37 and 38 of the center pin, which have been reduced in diameter to accommodate the smaller bore in the prebored work piece 39. The sizes of the cone sections 37 and 38 bear a definite proper relationship to the size and bore of the work piece to insure proper driving contact and desired concentricity as explained hereinabove.

In Figs. 10 and 11 the cup 10 has been maintained the same diameter as before but the sleeve 16 has been increased considerably in wall thickness. This produces a smaller diameter bore and thereby accommodates a smaller center pin. The exposed extension 36 of the sleeve has been reduced proportionately in diameter to fit the smaller diameter center pin, and to permit the tool which forms the finished outside diameter of the work piece to produce work of smaller diameter while still clearing this extended portion 36 of sleeve 16. The two cone sections 40 and 41 of this center pin are smaller in diameter than the corresponding cone sections shown in the preceding figures. As shown in Fig. 10, this smaller diameter double cone is adapted to pick up and center a work piece 42 having less overall thickness and a smaller hole than the work pieces shown in Figs. 1 and 8. This illustrates the

arrangement in which the cylindrical body portion of the center pin is changed in accordance with the internal diameter of the sleeve, and by which the external extended portion 36 of sleeve 16 may be reduced to permit the turning of small outside diameters without conflict between the cutting tool and the sleeve.

In Figs. 12 and 13 there is illustrated an alternative form of body portion and an alternative form of sleeve for the driving center. Instead of having the sleeve housed within the body portion, the latter is made solid and is shortened as indicated at 43, and the sleeve 44 is lengthened considerably. They abut each other and are fastened together by several tapped-in bolts 45. Five of these bolts are indicated in Fig. 13. It is to be noted that the body portion 43 in this embodiment is relatively short and that the reduced diameter portion 44 of the sleeve has been extended in length about twice that shown in the preceding figures. The purpose of this is to give better access to the work piece 46 from the driving center end. The center pin 21 and the cone sections 30 and 31 in this embodiment are substantially the same as those shown in Fig. 1. Another distinction between this embodiment and those shown in preceding figures is that no disk or base member 12 is used. Instead the driving dogs 13 are tapped directly into the body member 43.

In Figs. 14 and 15 I have shown an adaptation of my driving center to a solid (not prebored) work piece. In this case a small diameter stationary center pin 47 is used instead of the resiliently mounted center pin described above. This center pin is threaded into a stationary center core 48 and is adjustable endwise by turning with a screw driver inserted in the screw head shown at 49. By such adjustment the work engaging center point 50 may be advanced toward or retracted from the solid work piece 51. When the point center has been adjusted to the desired position it is locked in place by the screw 52, which is threaded in the same hole, and abuts the center 47.

The driving dogs 53 shown in Figs. 16 and 17 are like the driving dogs 13 of Fig. 3 except that the shank or body portion 54 is circular in cross section, instead of rectangular. They are therefore adaptable for use in a sleeve having either rounded slots or flat sided slots as mentioned hereinabove. These driving dogs are tapped into the disk member 12 as in Fig. 3, and to prevent rotation about their axes, locking screws 52, such as shown in Fig. 14, are provided. Also, each of the tapped ends has a screw head 49 for receiving a screw driver to adjust the dogs endwise, by rotation in the proper direction. When the locking screws 52 are turned up to give a tight fit with the screw head 49, the dogs are locked in firm, nonrotative position.

Various modifications and changes may be made in the above described devices, parts and arrangements thereof without departing from the scope of my invention, some of novel features of which are defined in the appended claims.

I claim:

1. A driving center comprising a supporting cup, a sleeve fixedly mounted within the cup and extending axially beyond the forward edge of the cup, said extension having a circular knife edge formed at the forward end face thereof, driving dogs supported by said sleeve, and a center slidably mounted within the sleeve for engaging the work.

2. A lathe driving center comprising a cylindrical body, a base member located therein, a concentric sleeve located within said cylindrical body and associated with said base member, a plurality of driving members connected with said base member, and cooperative means associated with said sleeve and driving members whereby said driving members are maintained in nonrotative driving position by said sleeve.

3. A lathe driving center comprising a center work engaging pin, a cylindrical body, a concentric sleeve surrounded by said body and having an extended portion of reduced diameter, the outer end of said reduced diameter portion being formed into a circular knife edge.

4. A driving center comprising a supporting body portion adapted to be attached to a driving mechanism, said body portion having a bore, a sleeve in said bore and supportedly fixed internally to said body portion, said sleeve having internal longitudinal elongated slots opening the length thereof into the bore of the sleeve, elongated work-engaging driving members located and maintained non-rotatably within the slots of said sleeve, and a work-engaging center member located within the bore of said sleeve in contiguous longitudinally supporting relation to said driving members.

5. A driving center comprising, in combination, a center member having a conical, work-engaging, outer-end portion, a concentric supporting sleeve in the bore of which said center member is located, an annular series of elongated longitudinal driving members in lengthwise contiguous relationship with said center member and located within radial, spaced, longitudinal slots provided in the sleeve wall and opening into the bore of the sleeve, and a cup-shaped body member in which said sleeve and center member are held in concentric operative relationship.

6. A driving center comprising a cup-shaped body, a sleeve and a cooperating supporting base housed within said body, elongated driving members connected at their inner ends to said supporting base and having their intermediate portions located in annularly spaced, longitudinal slots provided in said sleeve coincident with its bore, said driving members having projected, work-engaging, outer-end portions, and a work-engaging center member mounted within the bore of said sleeve in supporting relation to the contiguous portions of said driving members in the slots of the sleeve.

7. A driving center comprising a supporting body adapted to be attached to rotating means, a sleeve detachably secured coaxially to and having a portion of reduced diameter extending beyond said body, said sleeve having a plurality of longitudinal, polygonal, flat-sided, slots formed within its body portion opening lengthwise into its bore, a plurality of elongated, complementary

shaped, driving members located within and extending the length of said slots, and means within said supporting body and contiguous to the inner end of said sleeve for normally holding said so located driving members from longitudinal movement but permitting longitudinal adjustment of said driving members.

8. In a driving center having a supporting member adapted to be attached to a driving mechanism, a sleeve detachably secured coaxially to said supporting member, and a pointed center member located within the bore of said sleeve for centering a work piece, the combination of a base slidably and removably positioned within said supporting member, and normally held in place by the inner end of said sleeve, and a plurality of elongated, polygonal, flat-sided driving members located in complementary slots in said sleeve, opening lengthwise into the bore of the sleeve, said driving members being attached to said base and longitudinally adjustable with respect to said base.

9. A driving center comprising a supporting body member, having a forwardly extending outer cup portion, a concentric inner sleeve fitted and removably secured within and extending beyond said cup portion and presenting a squared work-engaging face of reduced diameter for accurate endwise positioning of the work piece, and a plurality of elongated, longitudinal driving members located within spaced longitudinal slots provided in the wall of said inner sleeve and opening lengthwise into the bore of the sleeve, said driving members having work-engaging ends projecting beyond said sleeve.

10. A driving center comprising a body portion, a sleeve supported thereby, said sleeve having longitudinal elongated slots spaced around its inner circumference and opening the length thereof into the bore of the sleeve, elongated work-engaging driving members located substantially throughout their length within the elongated slots of said sleeve, means maintaining said driving members non-rotatably therein, and a work engaging center member concentrically located within the bore of said sleeve, and engaging said driving members for holding them in their grooves.

11. A driving center as defined in claim 10 and in which the work-engaging center member and sleeve have cooperating means for preventing relative movement therebetween.

12. A driving center as defined in claim 10 and in which the elongated driving members are round and means are provided for locking them at their inner ends to prevent rotation.

13. A driving center as defined in claim 10, and in which the sleeve is coaxially attached to and in-line with the supporting body portion.

EDGAR A. TERRELL.
